US00D950309S

(12) **United States Design Patent** (10) **Patent No.:** **US D950,309 S**
Danieli et al. (45) **Date of Patent:** **** May 3, 2022**

(54) **CARBONATION MECHANISM**

(71) Applicant: **SODASTREAM INDUSTRIES LTD.**,
Kfar Saba (IL)

(72) Inventors: **Guy Danieli**, Jerusalem (IL); **Amit Avigdor**, Kibutz Bahan (IL); **Doron Krom**, Zichron Yaakov (IL); **Oren Shalev**, Ashdod (IL); **Allan Ring**, Mercaz Shapira (IL); **Avi Cohen**, Jerusalem (IL); **Dvir Brand**, Hod Hasharon (IL); **Amnon Shkedi**, Karkur (IL)

(73) Assignee: **SODASTREAM INDUSTRIES LTD.**,
Kfar Saba (IL)

(**) Term: **15 Years**

(21) Appl. No.: **35/510,465**

(22) Filed: **Apr. 2, 2020**

(80) **Hague Agreement Data**

Int. Filing Date: **Apr. 2, 2020**

Int. Reg. No.: **DM/207173**

Int. Reg. Date: **Apr. 2, 2020**

Int. Reg. Pub. Date: **Oct. 2, 2020**

(30) **Foreign Application Priority Data**

Oct. 10, 2019 (IL) 64252

(51) **LOC (13) Cl.** **07-99**

(52) **U.S. Cl.**

USPC **D7/397**

(58) **Field of Classification Search**

USPC D7/387, 397; D9/686

CPC B01F 3/04829; B01F 3/04794
See application file for complete search history.

(57) **CLAIM**

The ornamental design for a carbonation mechanism, as shown and described.

DESCRIPTION

1. Carbonation mechanism

1.1 : Perspective (front, top, left)

1.2 : Front

1.3 : Back

1.4 : Right

(Continued)

1.5 : Left**1.6** : Top**1.7** : Bottom

The broken lines in the drawings depict portions of the carbonation mechanism that form no part of the claimed design.

1 Claim, 5 Drawing Sheets
